J. JACOBS.

OILING DEVICE FOR FIBER SILK AND THE LIKE.

APPLICATION FILED NOV. 21, 1919.

1,397,522.

Patented Nov. 22, 1921.

Inventor
JOSEPH JACOBS

By his Attorney

Juliette H. H.

UNITED STATES PATENT OFFICE.

JOSEPH JACOBS, OF BROOKLYN, NEW YORK.

OILING DEVICE FOR FIBER SILK AND THE LIKE.

1,397,522.

Specification of Letters Patent.

Patented Nov. 22, 1921.

Application filed November 21, 1919. Serial No. 339,571.

To all whom it may concern:

Be it known that I, JOSEPH JACOBS, a citizen of the United States, and a resident of Brooklyn, in the county of Kings and 5 State of New York, have invented certain new and useful Improvements in Oiling Devices for Fiber Silk and the like, of which the following is a specification.

This invention relates to improvements in 10 oiling devices for fiber silk and the like.

The object of this invention is to provide an efficient inexpensive oiling device for fiber silk and the like, which is adapted to be used in winding machines for bobbins 15 and which is composed of few simple and easily adjustable parts, and which is durable and will not get out of working order.

Another object of this invention is to produce an oiling device for fiber silk and the like which will provide a thin and evenly 20 distributed film of oil upon a suitably mounted rotatable transfer element which the thread in its passage from the skein carriers to the bobbin is adapted to rotate.

25 Still another object of my invention is to mount at one edge of a suitable oil container, a roller adapted to contact with and be moved by a thread in the operation of winding the same on a bobbin, in combination with means, such as a wick, having one end in the oil supply and the other end in contact with said roller for supplying a thin film of oil to the roller, which is taken up by the thread during its passage over the 30 roller and which, by reason of the rotation thereof by the thread, always presents a fresh film of oil for the succeeding portions of the thread, whereby an even distribution of the oil on the entire length of thread is 35 procured.

40 With these and other objects in view, the invention comprises the combination of members and arrangement of parts so combined as to co-act and coöperate with each 45 other in the performance of the functions and the accomplishment of the results herein contemplated, and comprises in one of its adaptations the species or preferred form 50 illustrated in the accompanying drawings, in which:

55 Figure 1 is a diagrammatic view of a bobbin-winding machine showing the principle elements thereof and my improved oiling device in side elevation positioned intermediate such elements;

Fig. 2 is a longitudinal section on the line 2—2 of Fig. 3;

Fig. 3 is a top or plan view of the oiling device shown in Fig. 1; and

Fig. 4 is a section on the line 4—4 of 60 Fig. 3, looking in the direction of the arrow.

Referring now to these drawings which illustrate a preferred embodiment of my invention, 1 indicates the shaft of skein 65 carriers 2 of a bobbin winding machine, on which is mounted a skein 3 of fiber silk or like material, the thread 3^a of which, as shown, extends upwardly and is in the operation of being wound upon a bobbin 4 which, as shown, is mounted upon a vertical spindle 5 having a bobbin carrier 6 for supporting said bobbin 4. In the conventional bobbin-winding machine, a series of skein carriers, bobbin spindles, etc. are employed 75 and the parts just described merely constitute elements of such conventional form of winding machine for bobbins with which my improved oiling device is adapted to be used but in themselves form no part of my 80 present invention.

In the preferred embodiment of my invention one or a series of containers or cans 7 corresponding in number to the skeins which are being wound into bobbins, are 85 suitably supported on a supporting bar 8 extending, as shown, parallel to the shaft 1 and positioned intermediate the shaft 1 and the bobbin spindles 5. As illustrated, these containers are provided with side lugs 90

7^a and are secured to the support 8 by screw 7^b. Mounted, and as shown, journaled on a spindle 9 at the outer edge of the container 7 is a freely-rotatable roller 10 preferably composed of porcelain or other similar hard 95

or refractory material which, as shown, is provided with a depressed circular or rounded groove 10^a and is so mounted that a portion of its periphery will extend beyond the walls of the container so as to permit contact therewith and a rotation movement thereof by a thread 3^a in its passage from the skein to the bobbin. This rotatable roller is continuously supplied or fed with 100 a thin film of oil through capillary attraction by the wick 11 which, as shown, has one end thereof suitably retained in contact with the surface of said roller 10, as at 11^a, preferably at a point on the surface or periphery of such roller opposite to that 110

on which the thread travels, and the lower portion 11^b of said wick extends into the supply of oil contained in the container 7. The wick is, as shown, guided in a suitable 5 wick-guiding channel 12, one of the walls 12 of which is provided with openings 12^a through which extend wick-adjusting spur wheels 13 adapted upon manual rotation to adjust the contact of the wick with the 10 roller. The spur wheels 13 are, as shown mounted upon the usual spindle 14 which is suitably supported in the walls of the container and has a knurled knob 15 on the outside of the container to enable the manipulation 15 of the gears to adjust the wick in a manner similar to that of the ordinary lamp wick.

Having described my invention I claim:—

1. An oiling device for fiber silk and like 20 threads embodying a container provided with an oil containing portion, a roller having an unyielding, hard surface mounted to rotate freely above said containing portion and feeding means for supplying a thin film 25 of oil from the containing portion to said roller.
2. In oiling device for fiber silk and like 30 threads embodying a container provided with an oil containing portion, a roller having an unyielding, hard surface mounted on the container above said containing portion and adapted to rotate freely and feeding means for supplying a thin film of oil from the containing portion to said roller.
3. An oiling device for fiber silk and like 35 threads embodying a container having an oil containing portion, a roller having an unyielding, hard surface mounted upon a

container above said oil containing portion; having a portion of its periphery extending 40 beyond the walls of said container and adapted to rotate freely and feeding means for supplying a thin film of oil from the containing portion to said roller.

4. An oiling device for fiber silk and like 45 threads embodying an oil container, a roller having a non-yielding hard surface mounted adjacent to one edge of said container to rotate freely and having a portion of its periphery extending beyond the walls of said 50 container, and a capillary wick having one end retained in contact with said roller and its other end extending into said container and adapted to supply a thin film of oil to the said roller.

5. An oiling device for fiber silk and like 55 threads embodying a container having an oil containing portion, a grooved roller formed of a smooth glazed material mounted to rotate freely at one edge of said container and to have a portion of its periphery extending beyond the walls of said container, a wick having one end forced into contact with said roller and its other end extending into the oil-containing portion of said 60 container for supplying a thin film of oil to the said roller and means for adjusting the pressure of said wick against said roller.

In witness whereof, I have signed my name to the foregoing specification in the 70 presence of two subscribing witnesses.

JOSEPH JACOBS.
